UNITED STATES PATENT OFFICE.

EDWARD C. MEIER, OF PHOENIXVILLE, PENNSYLVANIA.

BAFFLE CONSTRUCTION FOR BOILERS.

1,260,426.

Specification of Letters Patent. Patented Mar. 26, 1918.

Application filed March 21, 1917. Serial No. 156,283.

To all whom it may concern:

Be it known that I, EDWARD C. MEIER, a citizen of the United States, residing at Phoenixville, in the county of Chester and 5 State of Pennsylvania, have invented certain new and useful Improvements in Baffle Constructions for Boilers, of which the following is a specification.

My invention consists of an improved 10 baffle construction for boilers. One object of my invention is to provide a baffle construction which will be strong and durable and which can be quickly and cheaply installed within a boiler.

15 Another object is to make a baffle construction in such manner that it can be readily secured between the tubes of water tube boilers and can be easily adjusted into various positions along the tubes of the 20 boilers.

Another object of my invention is to provide a specially constructed dividing baffle which will include fire brick so arranged 25 that it will protect its supporting structure against the direct heat and thereby lengthen the life of the latter.

These objects, and other advantageous ends which will be described hereinafter, I attain in the following manner, reference 30 being had to the accompanying drawings in which—

Figure 1 is a sectional elevation of a boiler illustrating my present invention.

Fig. 2 is a fragmentary perspective view 35 showing my improved fire brick baffle which is supported by angle bars which extend from side to side of the boiler casing.

Fig. 3 is a fragmentary side elevation showing one of my improved baffles as it 40 appears connected to the tubes of a water tube boiler.

Fig. 4 is an enlarged section on the line 4-4 of Fig. 3.

Fig. 5 is a transverse section through one 45 of the tubes and taken on the line 5-5 of Fig. 4.

Fig. 6 is a perspective view of an adjustable clamp which may be secured to a tube of a boiler unit as illustrated in Figs. 1, 3, 50 4, and 5, and which serves to support the baffle adjacent the tubes of the boiler.

Referring to the drawings, 1 represents the boiler casing having vertical front, rear, and side walls, the rear wall 2 having an 55 off-set or stepped portion 3 which connects with the upper vertical portion 4 of said

rear wall, the off-set portion being substantially horizontal and forming an indentation 5 in the rear wall.

An outlet passage for the products of combustion, is illustrated at 6, and a damper 7 is provided to regulate the amount of opening through said outlet passage, it being noted that a flue (not illustrated) can connect with said outlet passage and fit 65 within the space provided by the indentation 5.

Two boiler units 8 and 9 are arranged within the casing 1, the boiler unit 8 comprising a plurality of water tubes 10 connecting at their top and bottom with drums 11 and 12. The boiler unit 9 includes a plurality of tubes 13 which connect at their top and bottom with drums 14 and 15.

The drums 11 and 14 are connected by 75 tubes 16, and the drums 12 and 13 are connected by tubes 17, it being noted that the tops of the drums 11 and 14 are also connected by a tube 18 which acts as an equalizing tube between the steam spaces 80 of the drums 11 and 14.

The drum 14 has a main steam pipe 19 leading therefrom, and the drums 12 and 15 have blow-off pipes 20 and 21 connecting therewith. The drums 11, 12, 14, and 15 85 are arranged horizontally and supported within the side walls, the drum 12 being further supported by a pedestal 22 on the bottom of the casing.

The drums 11 and 12 are in different vertical planes so that the tubes 10 extend at an incline toward the front wall 23 of the casing. This is also true of the drums 14 and 15 so that the tubes 13 also extend at an incline and substantially parallel with the 95 tubes 10 of the boiler unit 8.

A grate 24 is provided adjacent the front wall 23 and at the bottom of the casing, thus producing a fire box 25 which is located forward of the boiler unit 8. A baffle 26 is 90 provided between the tubes 10 and extends upwardly from the drum 12 throughout a portion of the length of said latter tubes, stopping short of the drum 11 so as to provide a passage 27 for the products of combustion rising from the fire box 25.

A baffle 28, extending between the oppositely disposed side walls of the casing 1, is located between the tubes of the boiler units 8 and 9. This baffle 28 is arranged as 100 illustrated, substantially on a level with the top of the baffle 26 and includes two rows of

fire bricks 29 and 29^a which extend entirely across the boiler casing between the side walls. These rows of fire brick are supported by a supporting structure which includes a metallic plate 30 which forms a backing for the row 29 and extends from the bottom of said row to the bottom of the row 29^a, it being noted that a portion of the row 29^a overlaps the back of the row 29, thus 10 producing a stepped formation.

Angle bars 31 and 32 embrace the lower rear corners of the rows of brick 29 and 29^a respectively and at their ends are secured to the side walls of the boiler casing, another 15 angle bar 31^a being positioned under the row 29^a and against the plate 30.

It will be noted that by forming the supporting structure in the above manner, it is protected, by the rows of fire brick 29 and 20 29^a, from the direct heat of the products of combustion which pass upwardly over the baffle 26 and through the passage 27. This baffle 28 operates to divide the products of combustion in a manner hereinafter set 25 forth.

Another dividing baffle 33 is mounted below the baffle 28 and is of a construction substantially similar to said baffle 28 and includes two rows 34 and 35 of fire brick, the 30 row 34 being backed by a plate 36 and the lower, rear corners of said rows being supported by angle bars 37 and 38.

Another angle bar 39 fits under the row of bricks 35 and also bears against the plate 36 so that the supporting structure for the baffle 33 is identical with that described in connection with the baffle 28. This baffle 33 is located between the boiler units 8 and 9 and is arranged adjacent the lower end of a 40 baffle 40 which is positioned between the tubes 13 of the boiler unit 9 and extends downwardly from the drum 14. This baffle 40, at its lower end, stops short of the drum 15 and thus provides a passage 41 between its lower end and the drum 15.

The baffle 40 is made up of a number of fire brick tiles 42 which are designed to rest against the slightly inclined tubes of the boiler unit 9 and is composed of a plurality 50 of superimposed rows of said fire brick tiles, it being noted that each of the tiles has curved portions 43 on one surface designed to correspond with the outer surface of the tubes (see Fig. 5).

55 The lower row of tiles 42 has its bottom edge resting within the interior angle of an angle bar 44 which extends transversely of the boiler casing and to the rear of said tiles (see Figs. 1, 3, 4 and 5).

60 Clamps 45 are adjustably secured to the tubes by means of bolts 46. Each of the clamps is made in two sections 47 and 48 which are designed to surround the tubes, the section 48 of each clamp having an up-

wardly extending hook 49 designed to embrace the outer surface of the angle bar 44. 65

As illustrated in Fig. 3, each of the tubes, throughout the width of the boiler unit and against which the baffle tiles rest, is provided with a clamp 45, but it will be understood that any number of clamps may be used according to the weight of the tile and size of the boiler. For example, in some instances it may be only necessary to use one clamp for every other tube throughout the 70 width of the boiler unit or even a greater distance may be had between the clamps 45. 75

It will be noted, furthermore, that if it is desired to shorten the length of the baffle 40, one or more of the rows may be removed 80 by loosening the clamps 45 and moving them in such position as to permit the removal of the desired number of tiles 42 after which the clamps and angle bar 42 may be moved upwardly to again form the support for the 85 shortened baffle.

It will thus be understood that by the provision of the adjustable support, the baffle may be made of any length or held in any upright position between or adjacent 90 the tubes of a watertube boiler. I thus provide a simple construction which permits a baffle to be inserted between the tubes of a tubular boiler and supported in any position within the length of the tubes. 95

With the arrangement of the baffles 26, 28, 33, and 40, the products of combustion from the fire box 25 are compelled to pass upwardly between the tubes which are forward of the baffle 26, thence through the passage 100 27 whereby the drums 11 and 14, upper portions of the tubes 10, and the upper portions of the tubes 13 which are forward of the baffle 40, are heated. Then they pass downwardly between the baffles 26 and 40, 105 and in so doing are split up or divided by the baffles 28 and 33 causing them to pass between the rear tubes of the boiler unit 8 and the forward tubes of the boiler unit 9. Part of said products of combustion then 110 pass between the baffles 26 and 33 and serve to heat the drum 12 and adjacent tubes, thence move rearwardly and combine with the portion of products passing between the baffles 33 and the baffle 40, then all of said 115 products of combustion combine and pass through the passage 41 and upwardly to the rear of the baffle 40 and finally pass out through the outlet passage 6 to the flue.

I preferably form cleaning doors 35^a and 120 36^a in the side walls of the casing and arrange these doors above the baffles 28 and 33, so that any dirt collecting on the latter can be removed therefrom by a rake inserted through said doors. 125

A comparatively small drum 50 is located on the top of the boiler casing 1 and has a feed water inlet valve 51 connecting there-

with. The drum 50 is connected to another small drum 52 by straight pipes 53, said pipes extending through the casing 1 and into the interior thereof to the rear of the 5 tubes 13 of the boiler unit 9.

The drums 50 and 52 have openings 54 and 55 respectively, which are in direct alinement with the straight pipes 53. These 10 openings 54 and 55 are closed by plugs 56 and 57 during the operation of the boiler. Short pipes 58 connect the drum 52 with the drum 15.

In the construction illustrated in Fig. 1, it will be noted that the drum 52 is 15 partially embedded within the rear wall 2 of the casing and the opening 55 and plug 57 are located outside of said rear wall. This arrangement of the drums 50 and 52, and the pipes 53, permits the ready cleaning 20 through the openings 54 and 55 from the outside of the boiler casing.

The products of combustion after passing through the passage 41, will also serve to 25 heat the feed water preheating pipe 53 during the upward movement of said products and prior to their passing outwardly through the outlet 6.

It will thus be noted that by the above 30 described construction, a boiler is provided in which the hot products of combustion efficiently heat the several tubes, drums, and pipes, and the arrangement of the baffling and water preheating elements is such as to cause the absorption of the heat in an extremely efficient manner.

Furthermore, it will be noted that the 35 construction is such that it is easy for a man to get into the boiler casing and within the several chambers provided in order to efficiently clean the several parts.

While I have described my invention as

taking a particular form, it will be understood that the various parts of my invention may be changed without departing from the spirit thereof, and hence I do not limit myself to the precise construction set forth, but consider that I am at liberty to make such changes and alterations as fairly come within the scope of the appended claims. 45

Having thus described my invention, 50 what I claim as new and desire to secure by Letters Patent is:

1. The combination with a boiler having upright tubes spaced apart, of a baffle arranged adjacent certain of said tubes, said 55 baffle including superimposed rows of fire brick tiles spanning the space between said tubes and resting against one side of the latter, a bar positioned under the bottom tiles, and means adjustably supported on the 60 tubes for retaining said bar in position to support the baffle, substantially as described.

2. The combination with a boiler having upright tubes spaced apart, of a baffle arranged adjacent certain of said tubes, said 65 baffle including superimposed rows of fire brick tiles spanning the space between said tubes and resting against one side of the latter, a bar positioned under the bottom tiles, and means adjustably supported on the 70 tubes for retaining said bar in position to support the baffle, said means having hooks thereon, said bar being confined between the hooks and the tubes, substantially as described. 75

In testimony whereof I have signed my name to this specification in the presence of two subscribing witnesses.

EDWARD C. MEIER.
